CALIFORNIA.

COMBINATION BIT AND ROTARY UNDERREAMER.

ISSUED

1,169,922.

Specification of Letters Patent.

Patented Feb. 1, 1916.

Application filed November 13, 1915. Serial No. 61,309.

To all whom it may concern:

Be it known that we, LAWRENCE S. CAMPBELL and JOHN GRANT, subjects of the King of Great Britain, residing, respectively, at 5 Los Angeles, in the county of Los Angeles and State of California, and at Florence, in the county of Los Angeles and State of California, have invented new and useful Improvements in Combination Bit and Rotary 10 Underreamers, of which the following is a specification.

Our invention relates to improvements in combination bit and rotary under-reamers in which the cutters are collapsing when 15 shifted through the well-casing; and the objects of our improvements are, to provide a strong reliable tool; and to provide a tool of which the operating parts are inclosed in a strong shell, which has no holes or openings 20 of any kind in working position as well as in collapsed position, preventing sand or any other waste from entering the inside; the invention consisting in the construction, combination, and arrangement of devices 25 hereafter more fully described and claimed, and illustrated in the accompanying drawing, in which—

Figure 1 is a front view of our device, the outer shell shown in section. Fig. 2 is a side 30 view, the shell also in section. Fig. 3 is a cross section on line *a—a* of Fig. 1. Fig. 4 is a single cutter. Fig. 5 is the top of Fig. 1 with a locking key inserted. Fig. 6 is a cross section on line *b—b* of Fig. 5. Fig. 7 is a slight modification of the locking device, a pin inserted for the locking key. Fig. 8 is the lower end of a well-casing constructed 35 for using our device for rotary drilling.

Similar numbers refer to similar parts 40 throughout the several views.

Numerical 1, see Fig. 1, indicates the lower end of a working shell in well-work. The shell 1 is provided with a concentric bore 2 into which all the operating parts of my device are inserted. Near the termination of the bore 2, a projection 3 is left in the bore 2, to engage with a groove 4 in the center-block 5. Projections 3 and grooves 4 can be had in a suitable number, as will easily be understood, two being shown on the drawing, but one will usually be sufficient, as it serves only to keep the center-block in position in the bore. A suitable distance below the grooves 4, the center-block is cut down to a flattened shaft 6; farther to the lower end 55

this shaft is cut out more yet, to receive the nearly semi-circular shanks 7 of the cutters 8; and to the lowest end of the flattened shaft, lugs 9 are provided on the opposite sides to prevent the cutters 8 from falling out, in case of a break in the operating rods 10. The Fig. 3 is a section just above the top ends of the operating rods 10, showing these rods in the spaces left between the shell 1 and the flattened shaft 6; it also 60 shows a concentric bore 11, which is provided concentrically inside of the flattened shaft to receive a spring 12. The bore 11 also forms, in the flattened sides of the center-block, slots 33, through which the operating rods are inserted to engage with the springs 12. The lower ends of the operating rods 10 are turnably riveted in the holes 13 of the cutters 8. The tension of the springs 12 thus pulls the cutters 8 into the shell by 65 the operating rods 10.

The shanks 7 of the cutters 8 are constructed to form strong counter-levers and pounding surfaces. As the shell 1 forms a full ring-end, the cutters are provided with shoulders 80 14 to utilize this ring, forming a proportional large pounding surface. The tilting-moment, caused by the cutting pressure against the cutting edge 15 of the cutters 8, is counterbalanced by the resistance in the 85 long surface along the edge 16 of the shanks 7. The opposite edge is formed to prevent the cutters from collapsing, the edges 17 and 18 of the shank 7, see Fig. 4, engaging with the projections 19 and 20 on the flattened 90 shaft 6, see Fig. 1. To make the cutters collapse, as indicated in dotted lines at 21^a, see Fig. 1, the cutters have to be pulled out of the shell 1 far enough to disengage the edges 17 and 18 of the shank 7 from the 95 projections 19 and 20, the pulling being done against the tension of the spring 12. For taking our reamer apart, in this collapsed position, the whole operating parts, cutter-shanks and center-block, can be pushed in, a 100 suitable distance to bring the projection 3 in the shell 1 to the horizontal part of the groove 4, along which it can be turned to the vertical part of the groove, which is open to the upper end of the center-block 5.

To prevent a disengaging while operating with our reamer in a well, we provide a locking key as shown in Figs. 5 and 6. The key 21 is a straight flat steel bar, inserted 110 into a slot 22, which is cut through the whole

thickness of the center-block, but not through the shell. The key 21 naturally will always fall down to lock the projections 3 of the shell 1 in the groove 4 of the center-block, and this can only be unlocked by turning the whole reamer upside down.

A slight modification of our locking device is shown in Fig. 7, where a pin 25 is provided through the shell and center-block. The pin 25 is provided with a projection 26, which can be inserted through a notch 27 in the washer 28. The projection 26, naturally, turns down by its own gravity and locks the pin behind the washer 28. The washer is riveted in on the edges 29. At the opposite side of the shell 1, a small bore 32 is provided to drive the pin 25 out.

For using our device as a rotary reamer, we provide the lower end 30 of a well-casing with cut outs 23, see Fig. 8, to fit over our cutters 8. The lower end of the well-casing being usually the shoe and of thicker metal, we provide channels 24 on the inside of these shoes to allow water to pass through to the cutting edges 15.

For the case of a break in the operating rods 10, the cutters 8 are provided with a recess 31, see Fig. 4, to engage with the lugs 9 on the lower end of the center-block, see Figs. 1 and 2, preventing the cutters from falling out of the shell.

Having thus described our invention, we claim:

1. A device for the purpose described, consisting of a shell having a concentric bore with a projection formed near the inner termination of the bore, a center-block inserted into the bore of the shell being hollow at the upper end and flattened to the lower end and having a recess formed on the outside of the upper round end adapted to engage with the projection in the bore of the shell, cutters having shanks formed on the upper ends designed to fit in the nearly semi-circular spaces left on both sides of the center-block in the shell, a spring inserted into the hollow center-block, and operating rods with the lower ends turnably secured to the shanks of the cutters and engaging with the upper ends with the spring in the center-block adapted to hold the cutters in operating position.

2. A device for the purpose described, consisting of a hollow shell, a center-block removably secured in the shell, cutters slidably mounted in the space formed between the center-block and the shell, and a well-casing being cut out at the lower termination to fit over the cutters designed for rotary drilling and having grooves provided along the inside of the lower thicker end in the casing adapted to allow water to pass to the cutters.

3. A device for the purpose described, consisting of a shell being hollow and termi-

nating in a circular ring, a round center-block, removably secured in the shell being hollow at the upper end and flattened at the lower end, projections formed on the flattened part of the center-block, cutters having shanks formed on the upper ends slidingly fitting in the nearly semi-circular spaces formed on both sides of the flattened center-block in the shell and having shoulders to utilize the ring-termination of the shell for a pounding surface, the cutters having cutting edges on the lower end eccentric to the center of the device and a straight resisting shank on the upper end parallel to the center of the device opposite to the cutting edges, opposite to the straight resisting shank and on the same side with the cutting edges the shank is formed to engage with the projections on the center-block adapted to prevent the cutters from collapsing, and operating means secured to the cutters adapted to hold the cutters in operating position.

4. In a device for the purpose described, a hollow shell, a center-block removably secured in the shell being flattened at the lower end, cutters slidingly mounted in the spaces formed between the flattened center-block and the shell, said center-block having lugs formed on the termination of the flattened end, and said cutters having recesses formed on the sides toward the center-block adapted to engage with the lugs on the center-block to prevent the cutters from falling out.

5. A device for the purpose described, a hollow shell, a center-block removably secured in the shell being flattened at the lower end, cutters slidingly mounted in the spaces formed between the flattened center-block and the shell, said center-block terminating below the shell having means thereon to prevent the cutters from collapsing and also adapted to serve as a guide to bring the cutters into operating position, and operating means secured to the cutters adapted to hold the cutters in operating position, all substantially as described.

6. In a device for the purpose described consisting of a hollow shell, a center-block removably secured in the shell being flattened at the lower end, said center-block being also provided with a slot crosswise through the upper end, cutters slidingly mounted in the spaces formed between the flattened center-block and the shell, and operating means secured to the cutters and suitably supported by the center-block adapted to hold the cutters in operating position, the combination of a locking key inserted through the slot in said center-block adapted to prevent a disengaging of said shell and center-block.

7. In a device for the purpose described the combination with a hollow shell, and a center-block removably secured in the

shell being flattened at the lower end, of cutters having shanks on the upper ends slidingly mounted in the nearly semi-circular spaces formed on both sides of the flattened center-block in the lower end of the shell and having cutting edges formed on the lower ends of the cutters projecting off the shell in right angles to the flat side of the nearly semi-circular shanks.

In testimony whereof we hereunto affix 10 our signatures in the presence of two witnesses:

LAWRENCE S. CAMPBELL.
JOHN GRANT.
